United States Patent Office

Des. 226,511
Patented Mar. 20, 1973

226,511

CHAIR

Milton Stern, 1631 Walnut Ave., Wilmette, Ill. 60091

Filed June 14, 1971, Ser. No. 153,147

Term of patent 14 years

Int. Cl. D6—02

U.S. Cl. D6—68

The figure is a perspective view of a chair illustrating my new design.

The back of the chair is conventionally plain while the side not shown is substantially identical to the side shown.

I claim:

The ornamental design for a chair, as shown and described.
